[57] CLAIM

The ornamental design for a cosmetician caddy for holding eyeglasses and miscellaneous items and for displaying business cards, licenses, and photos, as shown and described.

DESCRIPTION

FIG. 1 is a top, front, and right side perspective view of a cosmetician caddy for holding eyeglasses and miscellaneous items and for displaying business cards, licenses, and photos showing my new design, the broken-line disclosure of a portion of a counter and of a paper within a translucent envelope being for illustrative purposes only and forming no part of the claimed design;

FIG. 2 is a right side elevational view thereof, the left side being a mirror image of that shown, illustrating the sloped pocket for holding eyeglasses, a tray for holding miscellaneous items, and a vertical envelope for displaying papers or photos;

FIG. 3 is a rear elevational view thereof; and,
FIG. 4 is a front elevational view thereof.
